VENT VALVE FOR STEAM RADIATORS

Ferdinand Jehle, Indianapolis, Ind., and Edwin A. Davies, Des Moines, Iowa, assignors to Hoffman Specialty Co., Indianapolis, Ind., a corporation of Illinois

Application July 1, 1942, Serial No. 449,264

17 Claims. (Cl. 137—122)

This invention relates to vent valves for use in steam heating systems, more particularly it relates to valves provided with means to cause rapid and efficient drainage of liquid from the valve casing back into the radiator.

In the copending application of William K. Simpson, Serial No. 297,521, filed October 2, 1939, which issued as Patent No. 2,289,218 on July 7, 1942, a valve construction is described in which the prior siphon drainage tube is replaced by a partition plate, which extends through the valve nipple, dividing it into upper and lower passages and providing for separate water and air drainage without the complications due to the use of the siphon drain tubes.

The present invention is an improvement over the said Simpson construction in which, instead of a fixed partition plate in the valve nipple, a hinged or movable or flexible plate is used to divide the nipple into upper and lower passages, the hinged or movable or flexible partition plate also providing for better controlled drainage of the valve.

It has long been recognized that if proper drainage of a valve casing after flooding is to be accomplished, more than a mere nipple connection between the vent valve and the radiator is necessary. That is, some mechanical addition is necessary to overcome any physical conditions retarding drainage of water from the flooded valve in order to start the drainage of water from the valve and to control the rate of drainage.

For many years this was accomplished by equipping vent valves with a siphon tube which passed horizontally through the valve nipple and projected downwardly from its outer end into the radiator section. However, the tendency of manufacturers to produce narrower radiator tubes has in some cases made it impossible to insert the heretofore used siphon tube valves without causing the tube to become wedged in, or in contact with, the back wall of the radiator section, and when this happens the siphon tube often is tilted in the nipple passageway in a position such that it impedes drainage rather than aids it and its contact with the back wall of the radiator section creates other objections as described in said Patent No. 2,289,218.

For best performance, a tongue valve, as distinguished from a siphon tube valve, should provide a space between the end of the tongue and the inside of the radiator tube, or the end of the valve nipple, which is always small enough

to be bridged by a sufficient quantity of water to cause a flow. This brings about prompt drainage of a flooded valve. In view of the differences in the depth and tappings of the vent valve bores in various radiators, it is desirable that the tongue be flexible or hinged and automatically adjustable to the various conditions of installation encountered in practice in order to provide automatically for proper spacing of the tongue from the radiator tube or valve nipple under all the various conditions of installations.

The object of the present invention is to provide a vent valve for steam heating systems having means to promote drainage of water from the valve casing back into the radiator under all conditions of normal operation and construction of the many types of column and tubular radiators and which drainage means will automatically accommodate or adjust itself to the construction of the particular radiator on which the valve is installed.

Another object of this invention is to provide an air vent valve for steam radiators adapted to quickly start the drainage of water present in the valve casing as the result of flooding of the valve.

A further object of this invention is to provide a vent valve capable of promoting drainage at a sufficiently rapid rate during flooding conditions to allow sufficient venting periods to enable the radiator to be heated in a reasonable time.

Another object of the invention is to provide a valve with drainage facilities that will function effectively regardless of whether the valves are of the vacuum or non-vacuum type.

Another object of the invention is to provide a self-draining vent valve which will be economical to construct and which will not get out of operation.

Another object of the invention is to provide a self-adjusting tongue for vent valves, which will automatically adjust itself to the condition of installation encountered in the particular radiator, so as to provide a substantially constant space between a projecting portion of the tongue and the nearest adjacent part of the radiator or vent valve nipple, so as to facilitate drainage of water between the projecting portion of the tongue and the radiator.

Another object is to provide a self-draining vent valve which can be installed in the standard openings of narrow radiators without contacting with the back wall of the radiator sec-

tion, and without in any way interfering with the drainage ports of the valve.

Various other objects and advantages of this invention will become apparent as the description proceeds.

In the accompanying drawings which illustrate preferred forms of construction embodying features of this invention:

Figure 1 shows a vent valve of the type to which our invention applies, having an adjustable or flexible tongue, in which the valve nipple is projected a maximum distance into a radiator with a short nipple boss.

Figure 2 shows an installation in which the valve nipple extends a minimum distance into the radiator with a long nipple boss, but in which the tongue of our valve nevertheless projects into the radiator tube or column.

Figure 3 is a vertical section on an enlarged scale of a radiator vent valve having a flexibly adjustable tongue and showing the detailed structure of the complete valve.

Figure 4 is a horizontal section along the line 4—4 of Figure 3.

Figure 5 is a vertical section of a nipple and a modified form of partition and tongue member.

Figure 6 is a vertical section of a modified partition member pivotally mounted in the nipple.

Figure 7 is a horizontal section taken on the line 7—7 of Figure 6.

Figures 8 and 9 are a vertical and horizontal view of a modified form of partition member.

Figures 10 and 11 are a vertical and horizontal view of another modified form of partition member.

Figure 12 is a vertical view of still another modification.

Figure 13 is a vertical view along the plane of the line 13—13 of Figure 12.

Figure 14 is a horizontal view of a partition plate fixedly mounted in a valve nipple and having a hinged tongue on the end thereof.

Figure 15 shows a valve nipple construction in which the tongue may be inserted from the front of the nipple after the nipple has been assembled on the valve casing.

Figure 16 shows a partition plate or tongue adapted for insertion from the front of the nipple; and

Figure 17 shows a valve nipple having a spring tongue installed and having a permanent downward bias or spring to keep the end of the tongue near the end of the valve nipple or radiator bore at all times.

The radiator construction illustrated in Figure 1 shows the valve 1 having a nipple 2, which projects into the radiator column 3 a maximum distance, due to the short boss 4 and the threading on the inside of the boss and on the valve nipple. In this construction it will be noted, however, that the adjustable tongue 5 which is the subject matter of our invention projects into the radiator column, and that the projection 6 from the tongue is spaced only such a short distance from the end of the valve nipple that a drop of water can bridge this space and start drainage of water from the valve.

In Figure 2 the nipple 2 is shown as projecting a minimum distance into the longer boss 4 of the radiator column 3. The difference in Figures 1 and 2 illustrates the variations encountered in installing vent valves on radiators of various types having long and short valve nipple bosses and threaded in different ways. It will be noted, however, in Figure 2 that the end

of the adjustable tongue 5 of the valve nipple still projects into the column 3 of the radiator and is spaced a short distance from the inside of the radiator boss, so as to promote the bridging of water across this space, which will cause the formation of drops of water to flow down the walls of the column 3 and promote drainage of water from the valve.

While the adjustable tongue of our valve may take various forms, as illustrated in the other figures of the drawings in all the forms, it is intended that the portion of the tongue from which the water starts to drip shall, regardless of whether it is installed in a long boss or a short boss radiator, be spaced a short distance from the nearest portion of the radiator or nipple to facilitate the forming of a water bridge which will start drainage from the valve.

A form of complete valve with which our invention may be used is illustrated in Figure 3 as including a valve casing 10 having a vent port 12 at its upper end and closed at its lower end by a base 14; a thermostatic float 20 enclosing a volatile liquid is mounted within the casing 10, and a valve pin 22 is supported by the float and adapted to engage the valve seat 13 of the port 12 when the float 20 is raised either by water flotation or by expansion of the volatile liquid therein. A nipple 30 projects laterally from casing 10 for connection to a radiator, and an adjustable partition member or tongue 40, which may take various forms as described hereinafter, is movably mounted in the nipple and projects outwardly beyond the edge of the nipple. While this valve illustrates a familiar type of construction, it will be understood that the adjustable tongue which constitutes our invention may be used with vent valves of various types of internal construction.

In normal operation a valve of the type illustrated operates in much the same manner as other valves of this type. The nipple 30 which is threaded externally is screwed into a tapping provided therefor in a radiator and this connects the interior of the radiator with the interior of the valve casing and provides a vent passage from the radiator to the atmosphere through the port 12 at such times when the valve pin 22 is not seated in its seat 13. The valve pin 22 closes the vent port and prevents any communication between the atmosphere and the inside of the radiator whenever water collects in the valve casing, and causes the hollow float 20 to rise and press the valve pin 22 into its seat. When the float 20 is not supported by water the diaphragm 24 rests on a supporting boss 16 which rises from base 14 and in this position the vent port 12 is open unless the temperature in the casing causes the volatile liquid enclosed in the float 20 to expand and distend the diaphragm 24 sufficiently to cause the valve pin 22 to be raised and pressed into contact with its seat 13. Such a valve will therefore permit the escape of air from the radiator through the vent port 12 but will prevent the escape of steam or water therefrom.

These valves, as illustrated in Figures 1 and 2, may take various positions with reference to the radiator, and it is intended that the adjustable tongue of our invention shall promote drainage of water from a flooded valve regardless of the position of the valve nipple in the radiator boss.

In the valve illustrated in Figure 3, the pivoted tongue 40 is so arranged that it will assume a position which will facilitate drainage of water from

the valve regardless of whether the valve nipple is screwed far into the radiator boss or only projects a short distance therein.

As illustrated, when the nipple projects only a short distance into the boss 4 of the radiator column 3, the space A between the pivoted tongue 40 and the inside of the boss 4 is such that drainage will be facilitated. If the nipple projects beyond the inner edge of the boss 4 in the manner illustrated in Figure 1, the pivoted tongue 40 will move downwardly by gravity and assume a position in which the space B between the tongue and the end of the valve nipple will be small enough to promote drainage of water from the valve.

In order to promote drainage of water from the valve back into the radiator after the valve has been flooded with water, which flooding occurs during a heating period when steam flows into the valve casing and condenses therein, or when water from steam condensing within the radiator itself surges into the valve, we may provide a hinged or spring plate or tongue of various forms in the nipple of the valve, which plate or tongue by accommodating itself to the position of the valve nipple in the radiator column or boss into which the nipple is screwed, promotes the drainage of water from the valve.

In Figures 3, 4 and 5, the partition member 40, which is used to facilitate and control the drainage of water from the valve casing back into the radiator, is in the form of a flat pivoted tongue movably mounted in an enlargement 32 in the nipple 30 to promote drainage when the water has flooded into the valve casing above the nipple. The partition member 40 separates the nipple bore into two passages, the upper passage serving as a conduit for air entering the valve from the radiator and the lower acting as a conduit for water leaving the valve and entering the radiator. Due to the pivotal connection of the member 40 in the valve nipple, the outer end of the partition member 40 will adjust itself to a position near the bottom 30a of the nipple 30 or the bottom of the nipple orifice or boss in the radiator, and the underside of the member 40 will act as a capillary leader along which water in the passage below the partition 40 will bridge until it forms a drop which will flow down the inside of the radiator column. Soon a second drop forms in the same way and once the flow of water back into the radiator has started, the air in the radiator under pressure will enter the valve to displace more water until all the water in the valve above the nipple passage has been drained out.

The plate 40 may be pivotally mounted on a pin 46 which may extend horizontally across the enlarged inner chamber 32 of the nipple 30 or across the narrower portion of the nipple. The plate 40 may be secured on the pin 46 by a turned over end 44. In Figure 5, the pin 46 is shown as mounted in the nipple passage itself instead of in the enlarged chamber, and the tongue is shown as having a rearward extension behind the pivot pin.

Instead of being pivotally connected in the valve nipple, the partition plate may be movably mounted therein as illustrated in Figures 6, 7, 8 and 9, in which the plates 50 and 51 are shown as provided with T shaped projections 42 which fit into slots 32a in the chamber 32 to hold the plates 50 or 51 movably in the valve nipple. The slots 32a may be closed by displaced lugs 32b or any other suitable means to prevent the pro-

jections 42 from becoming accidentally displaced from the slots 32a.

In Figures 6 and 7, a projection 50a has been struck from the tongue 50. This projection has two functions. It rests upon the threads of the radiator boss and supports the tongue 50 adjacent the inner end of the radiator boss when the valve nipple extends only a short way into the boss as illustrated in Figure 2 and promotes drainage between the tongue 50 and the lower inside edge of the radiator boss when in this position. When, however, the length and tapping of the radiator boss is such that the valve nipple extends therethrough as in Figure 1, the projection 50a is located at the projecting end of the valve nipple where it acts to cause bridging of the water at this point, causing the formation of drops which drain the flooded valve.

The projection 50a should be of sufficient length to bridge two or more threads in the radiator boss, so it will ride over the threads and not get caught thereon as the nipple is being screwed into the radiator.

Figures 8 and 9 show a projection 51a struck from the tongue 51 and serving the same purpose as the projection 50a.

In Figures 10 and 11 a removable tongue 52 is illustrated in which a projection 52a has been struck downward from the tongue and a central slot 44a provided, whereby the projections 42 of the tongue may be moved inward by springing the sides of the tongue so as to permit the tongue 52 to be inserted into or removed from the valve nipple from the front, without otherwise dismantling the valve. When in position the projections 42 fit within slots 32a in the valve nipple, as illustrated in Figures 6 and 7.

In this type of construction, the nipple can be assembled with the valve casing and the tongue inserted later. It is also possible with this type of construction to ship the assembled valves and supply the plumber or steam fitter with various length tongues, so that a tongue of the proper length can be inserted as the valve is being fitted to the particular radiator.

With removably mounted tongues as shown in Figures 10 and 11, it is therefore possible for the steam fitter to fit tongues of different lengths into the valve nipple to secure better the drainage of the valve according to the different depths of nipple openings or bosses in radiators.

To facilitate the assembly of this type of tongue into the valve nipple, the nipple 30 may be provided with slots 32a in which the projections 42 fit, as illustrated in Figure 15. To insert the tongue in the nipple, the sides of the tongue 52 are compressed and inserted in the bore of the nipple, and when the tongue has been inserted to the proper depth, the projections 42 are permitted to spring into the slots 32a.

In order to facilitate the flow of air into the valve casing, the end of the nipple nearest the casing is flared outwardly in an elliptical form, as indicated at 30b. This flare serves a purpose similar to the enlargement 32 in the valve nipple 30 of Figure 3.

In the form of embodiment illustrated in Figures 12 and 13, the tongue 53 is movably mounted in the nipple 30 and is provided with a centrally mounted projection 53a which is located beyond the end of the nipple 30 and rests upon the opening in the radiator bore and supports the tongue 53 a given distance above the radiator boss to give a regulated drainage from the

valve when the nipple is inserted to the position of Figure 2, and when in the position of Figure 1 the projection 53a acts as a water leader at the end of the valve nipple to cause bridging and the drainage of drops of water. The projection 53a will slide along the threaded bore of the radiator opening as the nipple is screwed into the radiator and will not interfere with the mounting of the valve on the radiator.

In Figure 14 the nipple 30 of the valve has a plate 54 mounted therein, and on the outer end of this plate a hinged tongue 54a is mounted by means of a hinge pin 55 or the like. A narrow projection 56 is formed on or integral with the tongue 54a to support the tongue a given distance from the end of the nipple 30 or a given distance from the walls of the opening in the radiator, to thereby facilitate drainage from the valve.

Figure 16 illustrates a modified type of spring tongue in which a projection 57a has been struck from the body of the tongue 57 and in which slots 52b have been cut in the tongue to permit springing it into place.

In Figure 17, the tongue 58 is of spring construction and is firmly mounted at its inner end 58a in the inner end of the valve nipple 30. The tongue 58 is, however, given a permanent downward bias or set before it is installed in the valve nipple, and when in position in the radiator it will always move near to the bottom of the bore in the radiator boss or near the bottom of the nipple bore. The curvature of the bore in the radiator or nipple will prevent the spring tongue from moving too far down, but the spring tongue 58 of Figure 17 will nevertheless always adjust itself to a position which promotes drainage of water from the valve.

For the best results, we have found that tongues such as 40, 50, 51, 52, 58, etc., should be sufficiently long to project through the radiator boss, which has been tapped to receive the vent valve, and into the radiator tube or column when the valve has been screwed into the radiator tapping a minimum amount as illustrated in Figure 2. However, the tongues should not be so long that when the valve is screwed into the boss the maximum amount as illustrated in Figure 1 the tongue will touch the far wall of the radiator tube.

As a specific example in commercial radiators of different types the length of boss has been found to vary from a minimum of $\frac{1}{16}$ " to a maximum of $\frac{1}{2}$ ", and the radiator tube dimensions of some radiators have been found to be as small as $\frac{5}{8}$ " x $\frac{7}{16}$ ". The preferred length of tongue of our valve under these conditions is one which projects approximately $\frac{1}{2}$ " beyond the edge of the nipple. This length insures a projection of the tongue into the radiator tube at all times, and yet assures that the tongue will not strike the far wall of the radiator tube regardless of how far the valve nipple is screwed into the radiator boss. The provision of projections such as 50a, 51a, 52a, 53a and 54a adjacent the end of the valve nipple insures support for the end of the tongue when the nipple is inserted the minimum distance as in Figure 2 and these projections also provide drainage means when the nipple is inserted the maximum distance as in Figure 1.

The width of the tongues 40, 50, 51, 52, 58, etc., also affects the drainage. In preferred embodiments the width of the tongue is made less than the diameter of the bore of the nipple but suf-

ficiently large to maintain a substantial lower passageway for the flow of water. The limited width coupled with the pivotal or movable connection gives the tongue a flexibility of movement. This permits the tongue to contact the edges of the walls of the tapping or the nipple and induce the flow of water. It also makes it possible to curve the projecting end of the tongue more than would ordinarily be possible while still retaining the ability to screw the valve into the tapping without danger of distorting the tongue. All the tongues shown in the drawings are so mounted in the nipple that they contact the edges of the outside of the nipple well below the center line.

Tongues provided with a drop lip or projection, such as those shown at 50, 51, 52, 53 and 54a in Figures 6, 9, 10, 12, 13 and 14, are also particularly well adapted to promote drainage. Tongues of this type are particularly suitable when the valve is screwed into the radiator tapping to such a degree that the nipple projects beyond the inside wall of the radiator. Under such circumstances without the drop lip or projection there is often a tendency for the flow of water to be arrested at the inside edge of the nipple and a definite hesitancy for it to drip over the edge by gravity. At such times the drop lip causes the water to bridge the gap and get it to a lower level where gravity again takes hold and pulls the water down. Several modifications of such drop lips are shown in the drawings. In Figure 6, the tongue shown is cut back from the edge to the center line in two places and the part between the cuts turned down at 90° . In the tongue shown in Figure 8, the drop lip was made by punching out a portion of the center of the tongue and bending the part in to form a diagonal line with the leading edge toward the nipple and the tailing edges extending toward the edge of the tongue. In this position, the inner edge of the drop lip is placed in line with the center of the nipple and the outside edge closer to the edges of the tongue. Another modification is shown in Figures 12 and 13. The tongue there shown is flat from end to end with a drop lip running longitudinally of the projecting portion.

We have found that projections of the type herein shown and described if placed at too great a distance from the end of the nipple will not help promote the flow and, therefore, the drainage of water, from the valve. The distance between the leading edge of the drop lip or projection and the nipple may vary from just touching to $\frac{1}{16}$ ". Projections placed within this range invariably promote the flow of water.

We have also found that when the tongues are provided with such projections there is little and in some cases no need for a curve in the projecting portion, particularly with the tongue shown in Figure 12.

While we have shown various forms of embodiment which our invention may take, it will be understood that still further embodiments and modifications may be made within the spirit of our invention and the scope of the appended claims.

We claim:

1. A vent valve for steam radiators, comprising a casing having a vent port and a lateral nipple for connection with a radiator, a float valve within the casing, and means in the nipple to cause drainage of water from the casing through the nipple comprising a substantially

horizontal plate-like partition member extending substantially from side to side of the nipple and movably mounted in the nipple and spaced from the bottom of the nipple and having an outwardly protruding portion extending beyond the end of the nipple, said movable partition member being constructed and arranged to automatically assume a position facilitating drainage of water from said valve.

2. A vent valve for a steam heating system, comprising a casing having a vent port and a lateral nipple for connection with the system, a float valve within the casing, and means in the nipple to cause drainage of water from the casing through the nipple comprising a substantially flat horizontal partition member extending substantially from side to side of the nipple and movably mounted for free up and down movement at the end of the nipple and having an outwardly protruding portion extending substantially beyond the end of the nipple and a member projecting downwardly from said outwardly protruding portion immediately adjacent but spaced from the end of the nipple to facilitate drainage of water from said valve.

3. A vent valve for a steam heating unit, comprising a casing having a vent port and a lateral nipple for connection with the heating unit, a float valve within the casing, and means in the nipple to cause drainage of water from the casing through the nipple comprising a substantially flat flexible partition member movably mounted for free up and down movement at the end of the nipple and extending substantially from side to side thereof and dividing the nipple into substantially equal upper and lower passages and having an outwardly protruding portion extending beyond and below the end of the nipple.

4. A vent valve for steam radiators, comprising a casing having a vent port and a lateral nipple for connection with a bore through the wall of a chamber to be vented, and means in the nipple to cause drainage of water from the casing through the nipple comprising a hinged partition member movably mounted in the nipple and having an outwardly protruding portion extending beyond the end of the nipple, and means connected to the partition member and spaced from the end thereof and from the end of the nipple adapted to support the end of the partition member adjacent the bore of the wall to facilitate drainage from the valve.

5. A vent valve for steam radiators, comprising a casing having a vent port and a lateral nipple for connection with a radiator, a float valve within the casing, and means in the nipple to cause drainage of water from the casing through the nipple comprising a horizontal partition member loosely mounted and vertically movable in the nipple and having an outwardly protruding portion extending beyond the end of the nipple, and means holding the partition member at a controlled distance from a cooperating drainage member facilitating drainage of water from said valve.

6. A vent valve comprising a casing having a vent port and a laterally extending nipple, a valve and float unit contained within the casing for closing and opening said port with the rise and descent of the float, and a movable tongue member pivotally mounted in the nipple and dividing the nipple bore into upper and lower passages, said partition member extending outwardly from the end of said nipple, and means to support the partition member at a controlled distance from

a cooperating drainage member facilitating drainage of water from said valve.

7. A vent valve for steam radiators, comprising a casing having a vent port and a laterally extending nipple for connection with a radiator, a float valve within the casing, and means in the nipple to cause drainage of water from the casing comprising a loose pivotally mounted substantially flat partition member projecting beyond the end of the nipple and extending substantially from side to side of said nipple and having a width less than the inside diameter of the nipple so that the free end of the member will fall below the end of the nipple and bridge across its end wall below the center line thereof.

8. A vent valve for steam radiators, comprising a casing having a vent port, a float valve within the casing and a laterally extending nipple on the casing for connection with a radiator, and means within the nipple to cause drainage of water from the casing through the nipple, comprising a substantially flat leaf spring partition member extending substantially from side to side of said nipple and having a downward bias mounted at the inner end of said nipple and extending therethrough and projecting outwardly therefrom beyond its outside diameter, said member dividing the nipple bore into upper and lower passageways.

30 9. A vent valve for steam radiators, comprising a casing having a vent port and a lateral nipple for connection to a radiator, a vent valve within the casing, and means in the nipple to cause drainage of water from the casing through the nipple comprising a partition member pivotally mounted at the inner end of said nipple and extending from side to side thereof and from back to front thereof and projecting therefrom, said member dividing the nipple bore into upper and lower passages, and the projecting portion of said partition member provided with a supporting member.

10. A vent valve for steam radiators, comprising a casing having a vent port and a laterally extending nipple for connection with a radiator, an enlarged chamber at the inner end of said nipple, a float valve within the casing, and means in the nipple to cause drainage of water from the casing through the nipple comprising a substantially flat horizontal partition member pivotally mounted at the inner end of said nipple and extending therethrough and projecting therefrom dividing the nipple bore into upper and lower passages, and a downward extension on the projecting end of said partition member, said downward extension being near enough to the edge of the nipple to cause bridging of water between the edge of the nipple and said downward extension.

60 11. A vent valve for steam radiators, comprising a casing having a vent port and a laterally extending nipple for connection with a radiator, a float valve within the casing, and means in the nipple to cause drainage of water from the nipple, comprising a loose substantially flat partition member pivotally mounted at the inner end of said nipple and extending therethrough and projecting therefrom, said partition member dividing said nipple into substantially equal upper and lower passages and being provided with a longitudinal slot to permit compression of the partition member at its inner end for insertion or withdrawal of the partition member from the outside through the nipple.

75 12. A vent valve for steam radiators, comprising

ing a casing having a vent port and a laterally extending nipple for connection with a radiator, a float valve within the casing, and means in the nipple to cause drainage of water from the casing through the nipple, comprising a pivotally movable substantially flat horizontal partition member extending through said nipple substantially from side to side and projecting therefrom with the outer end thereof projecting below the bottom of the nipple.

13. A vent valve for steam radiators, comprising a casing having a vent port and a laterally extending nipple for connection with a radiator, a float valve within the casing, and means in the nipple to cause drainage from the casing through the nipple, comprising a substantially flat tongue loosely fastened for pivotal movement at the inner end of said nipple, said tongue extending through said nipple and dividing the nipple into two substantially equal passages and projecting therefrom and curved downward at the tip with the curved tip of said tongue substantially below the bottom part of the nipple when in operating position.

14. A vent valve for steam chambers, comprising a casing having a vent port and a laterally extending nipple for connection with a steam chamber, a float valve within the casing, and means in the nipple to cause drainage from the casing through the nipple comprising a substantially flat tongue loosely fastened for pivotal movement on the inside of said nipple, extending substantially from side to side and through said nipple and projecting beyond the end of said nipple a distance sufficiently great to cause the tongue to project beyond the inside edge of the tapping and into the steam chamber into which the valve is screwed.

15. A vent valve for steam chambers, comprising a casing having a vent port and a laterally extending nipple for connection with a steam chamber, a float valve within the casing, and

means in the nipple to cause drainage from the casing through the nipple comprising a substantially flat tongue loosely fastened for pivotal movement on the inside of said nipple, extending substantially from side to side and through said nipple and projecting beyond the end of said nipple a distance sufficiently great to cause the tongue to project beyond the inside edge of the tapping and into the steam chamber into which the valve is screwed, said tongue having a slot beginning at the inner end thereof and spring portions at each side of said slot, whereby said tongue can be inserted into and removed from said nipple without removing the nipple from the valve.

16. The combination with a steam chamber of a steam heating system having a threaded boss into the steam chamber, of a vent valve having a venting port and a float controlled valve therein mounted in said boss, and a pivotally mounted tongue in the nipple of said vent valve extending substantially from side to side thereof and projecting from the end thereof into the steam chamber, and means on said tongue to support the tongue on the threads of the boss when the valve nipple is inserted a short way into said boss.

17. A vent valve for steam radiators, comprising a casing having a vent port and a lateral nipple for connection with a radiator, a float valve within the casing, and means in the nipple to cause drainage of water from the casing through the nipple comprising a substantially flat leaf spring partition member so mounted as to have a downward bias, movably mounted in the nipple and extending substantially from side to side thereof and having an outwardly protruding portion extending beyond and below and spaced from the end of the nipple to facilitate drainage.

FERDINAND JEHLE.
EDWIN A. DAVIES.
